US00D843403S

(12) **United States Design Patent** (10) Patent No.: **US D843,403 S**
Casse et al. (45) Date of Patent: **** Mar. 19, 2019**

(54) **DISPLAY SCREEN OR PORTION THEREOF
WITH GRAPHICAL USER INTERFACE**

(71) Applicant: **Fisher & Paykel Healthcare Limited**,
Auckland (NZ)

(72) Inventors: **Benjamin Wilson Casse**, Auckland (NZ); **Christopher Harding Campbell**, Auckland (NZ); **Katarzyna Sobolewska**, Auckland (NZ); **David Robert Keith Walker**, Auckland (NZ)

(73) Assignee: **Fisher & Paykel Healthcare Limited,**
Auckland (NZ)

(**) Term: 15 Years

(21) Appl. No.: 29/600,211

(22) E1-1 April 18, 2017

(22) Filed:
(51) LOC (1)

(57) **CLAIM**

The ornamental design for a display screen or portion thereof with graphical user interface, as shown and described.

DESCRIPTION

The FIGURE is a front view of a display screen or portion thereof with a graphical user interface showing our new design.

The broken lines showing a display screen or portion thereof form no part of the claimed design.
